LESTER L. JONES, OF ORADELL, NEW JERSEY.

TUNED RADIO FREQUENCY AMPLIFYING SYSTEM.

Application filed May 27, 1924. Serial No. 716,124.

This invention relates to tuned cascaded circuits embodying one or more electron discharge devices or tubes, and relates more particularly to an improved tuned radio frequency amplifying system.

The invention has special reference to the provision of a tuned radio frequency amplifying system designed and constructed for producing a maximum amplification efficiency combined with a maximum selectivity over a large wave length range, and for permitting efficient controlling, neutralizing or compensating of the capacitive feed back reaction which is due to the capacitive coupling between the grid and plate of the tube.

This application is a continuation in part of the following of my copending applications: Capacitive coupling control system, Ser. No. 607,046, filed Dec. 15, 1922; and Variometer, Ser. No. 614,404, filed Jan. 23, 1923, now Patent No. 1,664,513 patented April 3, 1928.

A prime desideratum of my present invention centers more specifically about the production of an amplifying system employing tunable circuits coupled in cascade in which the tuning of one of the circuits is accompanied by a predetermined change in the coupling coefficient between said circuit and an adjacent circuit in order to obtain the maximum amplification efficiency together with a constant and the greatest possible selectivity for each wave length.

A further prime object of my present invention comprehends the provision of an amplifying system of the nature referred to embodying one or more electron discharge tubes in which the capacitive coupling coefficient between the input and output circuits of the tube and the voltage on the plate are maintained constant over the whole wave length range, producing a system in which the energy retransfer from the output to the input circuit due to the grid-plate capacity of the tube is held invariant. Further and correlated objects of the invention include the provision of tuned radio frequency amplifying circuits in which the tuning is accomplished without producing any material variation in the shunt capacity of the grid or input circuits of the system, and the provision of a system of this nature in which the first input circuit is rendered independent of the size of the antenna and is virtually decoupled therefrom.

A still further and correlated prime object of my present invention centers about the production of, tuned cascaded circuits embodying one or more electron discharge devices in which any undesirable retransfer of energy from the output to the input circuit of the tube due to the grid-plate capacity is effectively controlled or compensated for in a uniform manner over the whole wave length range of the system.

To the accomplishment of the foregoing and such other objects as will hereinafter appear, my invention consists in the elements and their relation one to the other as herein-after particularly described and sought to be defined in the claims; reference being had to the accompanying drawing which shows the preferred embodiment of my invention, and in which:

Fig. 1 is a wiring diagrammatic view showing some of the principles of my invention applied to a radio receiving system of the tuned radio frequency amplifying type, and showing the use of my variometer and variotransformers for linking the circuits,

Fig. 2 is a view showing diagrammatically the construction and arrangement of the interlinking variometer and variotransformers,

Fig. 3 is a view showing the manner in which the parts of the variometer are preferably connected,

Figs. 4 and 5 are views respectively of the design of variotransformers employed in the first and second radio frequency stages of the system, and

Fig. 6 is a wiring diagrammatic view of the radio receiving system having two stages of radio frequency amplification and one stage of audio frequency amplification showing the principles of my invention applied for producing inductive tuning of the interlinked circuits and for controlling the capacitive feed back of the electron discharge devices.

Referring first to Fig. 1 of the drawings, I show the principles of my invention applied to a radio receiving system of the tuned radio frequency amplification type embodying preferably though not necessarily two stages of tuned radio frequency amplification. This system comprises a plurality of electron discharge devices a , a' and a^2 each including a cathode or filament 20, a grid 21, and an anode or plate 22. The electron discharge device a is provided with an input or grid cir-

cuit generally designated as i connected to an energy receiving circuit such as the antenna circuit n , and is provided with an output or plate circuit generally designated as o which 5 is linked to an input or grid circuit i' associated with the electron discharge device a' by means of a variotransformer V' described more in detail hereinafter and embodying my invention as disclosed and claimed in the 10 aforementioned copending application Ser. No. 614,404.

The electron discharge device a' is also provided with an output or plate circuit o' which is linked to an input circuit i^2 associated with 15 the electron discharge device a^2 by means of a second variotransformer V^2 . The electron discharge device a and the linking structure V' forms the first radio frequency amplification stage, and the electron discharge device a' and the linking structure V^2 forms 20 the second radio frequency amplification stage, the electron discharge tube or device a^2 forming the detecting stage, this tube being provided with the output circuit or telephone circuit o^2 .

In the preferred embodiment of my invention, each of the input circuits is inductively tuned, and preferably to the frequency of the radio waves desired to be selected. For in 30 ductively tuning the first input circuit i which connects the grid 21 to the negative terminal of the battery A , the input circuit is provided with the variable inductance or variometer V of my invention, the said variometer comprising 35 a stator S and a rotor R each composed preferably of a plurality of coils of the double D type as hereinafter described more in detail, the construction diagrammatically depicted in Fig. 1 showing the double D sections of the rotor R and the stator S arranged coaxially and connected across the input circuit, the opposite ends of the variometer being connected to the antenna n and to ground g .

45 For inductively tuning the input circuit i' , the variotransformer V' comprises a variable secondary L_2 having a construction similar to that of the variometer V and including the coaxially arranged rotor R and stator S each 50 of the double D section type, the said variable secondary being connected to the grid 21 of the tube a' by means of the conductor 23 and to the negative terminal of the battery A by means of the conductors 24, 25 and 26. The 55 primary of the variotransformer V' comprises a coil L_1 which is inductively related to the variable secondary L_2 and preferably coupled to the stator coil S thereof and arranged coaxially with both the stator and rotor of the secondary, all as will be described more in detail hereinafter and as is diagrammatically depicted in Fig. 1. The primary L_1 is arranged in the output circuit o of the 60 first tube a and is connected to the plate 22 by means of the conductor 27 and to the posi-

tive terminal of the battery B by means of the conductor 28, the A and B batteries being connected together by the conductor 29 as shown in the drawings.

For inductively tuning the input circuit i^2 , 70 the variotransformer V^2 is provided with the variable inductance or secondary L_2 which includes the rotor R and the stator S of the double D section type having a construction similar to that heretofore described in connection with the variotransformer V' , the said secondary L_2 being connected to the grid 21 by means of the conductor 30, the integrating device 31 and conductor 32, and being connected to the positive terminal of the A battery by the conductors 33, 34, 35 and 36. The primary L_1 of the variotransformer V^2 is also arranged coaxially with the rotor and stator of the secondary as diagrammatically depicted in Fig. 1, and is also composed preferably of a coil of the double D section type connected to the plate 22 of the tube a' by means of the conductor 37 and to the positive terminal of the B battery by means of the conductor 38.

90 The output circuit o^2 is provided with the current detecting means such as the telephone 39 connected at one end to the plate 22 by means of the conductor 40, and at the other end to the positive terminal of the B battery 95 by means of the conductor 41, the usual condenser 42 being connected in shunt to said telephones. For heating the filaments of all the electron discharge devices to incandescence to produce the electron emission, the same are connected to the A battery, the filament 20 of the device a being connected to one terminal of the battery by means of the conductors 43 and 36, and to the other terminal of the battery by means of the conductor 44, rheostat 45 and conductors 46 and 26, the filament 20 of the device a' being similarly connected to the battery A and to the rheostat 45 by means of the conductors 47 and 48, while the filament 20 of the device a^2 is connected 105 to one terminal of the A battery by means of the conductors 49, 34, 35 and 26, and to the other terminal by means of the conductor 50, rheostat 51, and conductors 52, 25, 46 and 26.

110 As heretofore stated, a prime object of my present invention centers about the production of a system employing tunable circuits coupled in cascade, in which the tuning of one of the circuits is accompanied by a predetermined change in the coupling coefficient between said circuit and an adjacent circuit. I have discovered by empirical determination in tuned radio frequency amplifying systems, that in order to obtain the maximum amplification efficiency, together with a constant and the greatest possible selectivity for each wave length, the coupling coefficient between adjacent circuits should be varied in the same direction and progressively with the wave length variations so that at the smaller waves 120

the coupling should be relatively loose, and at the longer waves relatively close or tight.

To accomplish the desired results, in the preferred embodiment of my invention the coupling between the cascaded circuits is made of the inductive type and the tuning of the circuits is effected inductively as already explained. Although in the preferred embodiment I show the inductive coupling combined with the inductive tuning, it will be understood however that the invention is not limited to the inductive coupling and tuning type, and that the principles of the invention may be carried out with other types of coupling and tuning. The inductive type is preferred, however, for the numerous advantages offered thereby, which will become apparent as the description of the various features of my invention proceeds.

In this preferred inductive coupling and inductive tuning of the invention, the desired coupling coefficient and tuning variations are produced by the design and construction of the variotransformers used in the first and second tuning stages. These variotransformer units generally shown in Fig. 1 are diagrammatically depicted in Figs. 4 and 5 of the drawings, Fig. 4 relating to the variotransformer used in the first stage, and Fig. 5 to that used in the second stage, the construction of the variable secondary of these variotransformers being more accurately illustrated in Fig. 2 of the drawings, and the connection thereof in Fig. 3 of the drawings.

Referring first to Fig. 2 of the drawings, the variable secondary or variometer constructionally comprises a rotor including a set of coils and a stator also including a set of coils, the coils of the stator set and the coils of the rotor set being arranged in interleaving alternating relation after the manner of the stator and rotor plates of a variable air condenser, and as shown diagrammatically in Fig. 2 of the drawings, the rotor R comprises the set or plurality of rotor coils r_1, r_2, r_3 , and r_4 arranged in alternation with the set or plurality of coils s_1, s_2, s_3 , and s_4 of the stator S. The rotor and stator coils, as will be understood, are arranged in closely spaced superposed relation, and are shown in Fig. 2 displaced laterally only for purposes of clarification and for facilitating the tracing of the circuits in the independent stator and rotor coils.

The stator coils are each wound so as to produce a winding in a single plane, the winding comprising two coil sections for producing magnetic fields in opposite directions, each of the coils to this end comprising the two coil sections 10 and 10' wound in opposite directions and presenting a double D formation, this being indicated by the arrows showing the momentary direction of flow of current in the windings to produce a field in

the coil section 10 in one direction as indicated by the circles 11 and a magnetic field in the coil section 10' in the opposite direction as indicated by the cross 11'. The stator coils are connected together so that their mutuals add, and to this end the oppositely positioned coil sections 10 and 10' are electrically connected by conductors 12 and the end coils are connected to the terminals 13 and 13' by means of the conductors 12^a and 12^b respectively. With this arrangement and interconnection, it will be seen that the magnetic flux threads up through the coil sections on one side and down through the coil sections on the other, producing a magnetic field which is closed substantially within the confines or dimensions of the coils, thus minimizing any external magnetic field.

The rotor coils r_1 to r_4 are each similarly constructed, comprising two sections 14 and 14' producing a double D coil, the sections being wound in opposite directions as clearly indicated by the arrows in the figure to produce oppositely directed magnetic fluxes as shown by the circles 15 and the crosses 15'. These rotor coils are also interconnected so that the mutuals therebetween add, and to this end some of the coil sections 14' are connected by means of the conductors 16 and some of the coil sections 14 are connected by means of the conductors 16', the end coils being connected to the terminals 17 and 17' by means of the conductors 16^a and 16^b respectively. To obtain the desired direction of the fluxes with this interconnection, it will be noted that the coils r_2 and r_4 are inverted with respect to the coils r_1 and r_3 , the connection between the coil sections of the first set of coils being on one side of the rotor axis, and the connection between the coil sections of the other set being shown on the other side of the said axis. With this arrangement it will be also noted that the magnetic flux threads through all the rotor coil sections in a manner to minimize an external magnetic field.

Still referring to Fig. 2, the rotor coils are shown arranged in alternation with the stator coils, and when the same are superposed in the position shown in Fig. 3, the mutuals oppose to produce a minimum inductance. With this construction it will be seen that as the rotor is rotated from the position shown to a position of 180° thereto, the mutuals will change from full opposing to full aiding, and in the latter position the fields of equal magnitude will aid each other to produce a maximum inductance value. To accomplish this latter end, the rotor coils are preferably made equal in number to the stator coils, and are similarly wound to produce like physical dimensions.

The stator and rotor coils may be connected either in parallel or in series, and when it is desired to connect the stator and rotor coils

in series, the manner of connection shown in Fig. 3 of the drawings may be adopted, the stator coils S and the rotor coils R being connected together only at one end as shown. 5 With this series connection, a very large inductance and wave length range may be obtained, the distributed capacity as represented by the condenser C' being somewhat greater than that for the parallel connection.

10 Referring now to Figs. 4 and 5 of the drawings, I show the preferred design and construction of the variotransformers, each consisting of the primary L_1 of the double D type and the secondary L_2 which is in all respects 15 like the variometer shown in Fig. 2 and described hereinbefore. The double D rotor and stator coils are shown in Figs. 4 and 5 as r_1 , r_2 , r_3 , r_4 , and s_1 , s_2 , s_3 , and s_4 , in a conventional manner for purposes of simplicity, it being 20 understood, however, that the design is of the double D type more accurately depicted in Fig. 2. It will be noted that for the first stage variotransformer (Fig. 4) the primary L_1 is arranged at the end of the unit and is coupled 25 to a stator coil (s_1), while for the second stage variotransformer (Fig. 5) the primary L_1 is arranged between the end stator and rotor coils s_1 — r_1 , and is coupled to the stator coil for reasons that will become clearer herein- 30 after.

To produce the desired coupling and tuning variations, the variotransformer units V' and V^2 must be accurately designed, and this includes a determination of

35 1. The maximum and minimum inductance of the secondary L_2 ,
2. The positioning of the primary or plate coil L_1 , and
3. The magnitude of the mutual M between the primary L_1 and the secondary L_2 and the resulting value or magnitude of the primary, each of which is determined by one or more factors as follows.

40 45 (1) *Factors determining the maximum and minimum values of the inductance of the secondary.*

The maximum wave length desired and the grid shunt capacity to be used, as hereinafter 50 explained, determine the maximum inductance of the secondary of the variotransformer; and in the preferred construction this is made 640 micro-henrys. The minimum inductance is determined by the shortest wave 55 length required; and this minimum is obtained by reducing the spacing between the double D coils, the closer the coils the less the magnetic leakage, and the lower the minimum inductance and wave length. In the preferred embodiment of the invention, a spacing of two-tenths of an inch between the rotor and stator coils which gives a minimum inductance of 75 micro-henrys and a ratio of about 60 8.5 to 1 is used, this being found ample and

efficient for covering the broadcast range of 65 wave lengths.

(2) *Factors determining the position of the primary or plate coil.*

The position of the primary or plate coil 70 relative to the variometer or secondary coils depends upon the manner in which it is desired that the coupling coefficient or mutual inductance vary with the wave length; and I have empirically demonstrated, as will become clearer presently, that the desired variations should range from (a) the mutual inductance varying somewhat greater than proportionately with the wave length to (b) the 75 mutual inductance varying as the square of the wave length so that the coupling coefficient increases at all times with the wave length of the secondary. In a general way, as will be shown presently, the variation of the mutual inductance is with a higher power 80 of the wave length, the nearer the plate coil is to the center of the variometer coils.

85 For example, in the variotransformer of my invention I provide two primary coils L_p and R—P (see Figs. 4 and 5) only one 90 of which is used as the plate coil. One of these coils is at the outer end of the variotransformer and is separated from the other by the rearmost stator coil s_1 . The second 95 primary coil is therefore between the rearmost stator and a rotor coil of the variometer. The manner in which the mutual inductance varies with the wave length depends upon which of these two primary coils is 100 used as the plate coil.

In the first stage variotransformer (Fig. 4) I use, as already stated, the outside coil 105 as the plate coil, with the result that the mutual inductance varies somewhat faster than proportionately with the wave length and therefore the coupling coefficient

$$(K = \sqrt{\frac{M^2}{L_1 L_2}})$$

110 increases less than proportionately with the wave length, as will be seen from the following tabulation:

Variometer	Actual mutual in micro-henrys	Theoretical mutual	115
Maximum.....	97	97	
90°.....	58	72	
Minimum.....	23.5	33	120

The theoretical column above is calculated on the assumption that the mutual varies as the wave length or so as to obtain a constant coupling coefficient.

125 In the second stage variotransformer, the variation of the mutual desired is as the square of the wave length or so as to obtain

a coupling coefficient varying directly with the wave length; and in this second stage variotransformer, the inside primary coil is used for the plate coil, with the following 5 results:

Variometer	Actual mutual in micro-henrys	Theoretical mutual
10 Maximum	128	128
90°	70.5	70.5
Minimum	12.85	15.0

It will therefore be seen that in the one 15 case I use a coupling coefficient which increases slightly with the wave length, and in the second case I use a coupling coefficient which increases almost exactly proportionately with the wave length, and also that the 20 variation is sharper the nearer the plate coil is to the center of the variometer unit.

(3) *Factors determining the value of the mutual inductance and inductance of the plate or primary coil.*

Having determined the position of the plate coil, from the above considerations (namely the type of variation of mutual inductance or coupling coefficient desired) I 30 next fix the inductance of the plate coil. This is selected in general so as to get a high amplification efficiency at the long (or any) wave length, and so as to avoid so high an inductance as would create a primary circuit 35 nearly resonant to the shortest wave length. Such a resonant circuit might be formed from the plate and compensator coils shunted by the tube capacity and a portion of the previous input circuit inductance and capacity. For determining the magnitude of 40 the mutual M , recourse must first be had to the factors of amplification efficiency and selectivity.

(a) *The factor of amplification efficiency and conditions governing the same.*

I have empirically discovered that the highest energy amplification from practically any type of tube is had by inserting 50 an impedance in the output circuit of the tube equal to approximately one half the plate filament impedance of the tube. Present day tubes operating with proper "C" batteries have plate filament impedances ranging 55 from 20,000 to 40,000 ohms so that the tube output circuit impedance should be approximately 10,000 to 20,000 ohms and I select an average of 15,000 ohms.

In order to have high amplification efficiency in the tuned amplifier operating over 60 a broad wave length band, it is highly desirable to hold or maintain this impedance of the output circuit of the tube up to approximately 15,000 ohms selected. The impedance 65 of the primary coil is relatively low, having

usually an average value of about 500 ohms for the broadcast wave length band. The greater part of the output impedance must therefore be the equivalent secondary impedance reflected into the primary. When the 70 secondary is tuned to resonance the resistance reflected in the primary is:

$$R'_1 = \frac{\omega^2 M^2}{R_2} \quad (1) \quad 75$$

where M is the mutual, ω is 2π times the oscillation frequency and R_2 the ohmic resistance of the secondary circuit. R_2 being determined by considerations of sharpness of tuning, this equation determines M 80 for any given wave length, and therefore the inductance of plate or primary coil. To maintain high amplification efficiency this reflected resistance must be held constant over the wave length range, to the output impedance empirically determined, namely, 15,000 ohms or more (up to 30,000 ohms). With this value of the reflected resistance empirically arrived at, the values of the mutual M 85 and the ohmic resistance R_2 of the secondary 90 may now be determined.

(b) *The factor of selectivity and conditions governing the same.*

Before completely determining the value 95 of M , it is necessary to consider the secondary resistance, because this is intimately related to the selectivity of the amplifier.

Assuming that it is desired to make each 100 stage as selective as possible, it is necessary to find how far to go. General theory teaches that in order to amplify modulated waves without distortion, the amplifier must transmit all of the wave frequencies carrying the modulated energy. This band of frequencies 105 consists of that group ranging from the carrier frequency less the highest modulation frequency, to the carrier plus the highest modulation frequency. In a practical way 110 this band is one lying 3,000 cycles each side of the carrier frequency. This condition may be translated into my tuned amplifier 115 design by postulating that the resonant circuit shall be so broadly tuned that the highest and lowest frequencies of this band shall produce voltage effects no less than $\frac{1}{16}$ of the effect produced by the mean or carrier frequency. To further relate this condition to the resonant circuit of my invention, I 120 may say that the decrement of the resonant circuit for this broad casting band should be of the order of .02 to satisfy this condition. For example, if a resistance of $2\frac{1}{2}$ ohms is given to the secondary circuit at 200 125 meters, where the inductance is 75 micro-henrys and the capacity 150 mfd., the resulting decrement will be .0116. The sharpness of resonance (i. e. the detuning factor for $\frac{1}{16}$ voltage effects) of such a circuit corresponds to 2620 cycles change of frequency 130

at this wave length and to only 850 cycles at 600 meters showing that such low decrement would produce appreciable distortion on the long waves. It will be seen, therefore, 5 that the amplifier should be operated with appreciable ohmic resistance in the secondary circuit.

Having found by experiment, that approximately 2½ ohms of real ohmic resistance in the secondary circuit at 200 meters is required, for stable operation, I insert this value in equation (1), and find that the necessary mutual is approximately 20 micro-henrys. This value together with the secondary inductance and the predetermined position of the plate coil as hereinbefore arrived at determines the inductance of the plate coil. In my present embodiment this inductance is about 90 micro-henrys.

20 The foregoing considerations aid in explaining the physical basis of the feature of my invention which relates to the simultaneous increase of coupling co-efficient with wave length. In the inductively tuned secondary 25 the resistance of the secondary, besides being appreciable as above indicated, should increase with the wave length. The increase of this resistance is determined by two factors, namely, the characteristic of constant 30 selectivity and the characteristic of the greatest possible selectivity for each wave length. For obtaining constant selectivity, the log. dec. should be constant, and for obtaining the greatest possible selectivity on all wave 35 lengths, the log. dec. should vary proportionately with the wave length, as given in the following equation:

$$\delta = \pi R \sqrt{\frac{C_2}{L_2}}$$

40 where $R = R_2 + R_2' - R_{2P}$ as defined hereinbelow. For constant selectivity since L_2 , the inductance of the secondary increases as the square of the wave length, R must increase 45 with the wave length to hold this log. dec. constant. For obtaining the greatest possible selectivity on all wave lengths and the log. dec. varying proportionately to the wave length as stated, it follows that R must vary 50 as the square of the wave length.

The resistance R of the secondary is composed of three parts:

1. The ohmic resistance of the secondary circuit which is designated R_2 .
- 55 2. The resistance of the primary circuit (substantially the filament plate resistance of the tube) reflected into the secondary circuit which is designated as R_2' .
3. The negative resistance introduced into 60 the secondary through the capacitive feed back action of the succeeding plate circuit. This is introduced in the form of a voltage acting on the secondary circuit in phase with the secondary current. This negative resistance is designated as $-R_{2P}$.

I have found that good results are to be obtained when the resistance reflected from the primary into the secondary (R_2') is of the same order of magnitude as the ohmic resistance of the secondary. By this I mean 70 that R_2' shall be from 1 to 2 times R_2 . This division leads to freedom from local oscillations through all practical variations of the tube impedance. The sum of these two is reduced by 50% to 75% because of the subtraction of R_{2P} .

Now if we refer to equation (1) : $R_2' = \frac{\omega^2 M^2}{R_2}$ we see that in order to obtain the constant selectivity, the mutual (M) must vary as 80

the $\frac{3}{2}$ power of the wave length, since R_2 (which with the values selected substantially equal R) varies as the wave length. It is also apparent from this equation (1) that to obtain 85 the greatest selectivity at any wave length, the mutual M must vary as the square of the wave length, since R_2 varies as the square of the wave length.

It therefore will be seen that for each 90 stage, to obtain the optimum conditions, the mutual should vary between the $\frac{3}{2}$ power and the square of the wave length. In the practical embodiment of the invention this range of values is adopted, and as heretofore shown, I select for the second tuning stage of the system a mutual varying as the square of the wave length, while for the first tuning stage I select a mutual which varies somewhat less than the $\frac{3}{2}$ power of the wave length, the lesser value being selected for the purpose of compensating for changes in the losses of the first input circuit which take place with 105 change in wave length, as will be further explained hereinafter.

The above considerations are theoretical and apply more closely to practical cases the greater the number of cascaded stages, assuming that all external feed back be eliminated, this for the reason that all intermediate stages have input circuit resistances which are reducible by an amount corresponding to the tube capacitive feed back reaction, whereas the last stage usually has a higher decrement than the intermediate stages. These theoretical considerations are important, however, because the selectivity 110 of the system tends to become that power of the selectivity of the average of the selectivities of each stage corresponding to the number of stages.

The principles of my invention thus far described show the adaptability of my system to tuned radio frequency circuits in which the capacitive feed back reaction due to the grid-plate capacity is compensated for, neutralized or suitably controlled.

In cascaded circuits in which the secondary circuit is capacitively tuned, the capacitive coupling co-efficient between the grid and plate circuits of a tube

$$(K' = \sqrt{\frac{C_p^2}{C_s C_p}}, \text{ where } C_p \text{ is small compared with } C_s + C_p)$$

- 5 instead of remaining constant, will vary with the tuning of the secondary, increasing sharply with the decreasing wave length, with the result that the energy retransfer or feed back increases, this energy retransfer 10 being proportional to $K' \times V$ where V is the voltage on the plate. The ideal condition is where both K' and V are constant, since it is desired that the feed back due to the capacitive coupling be a constant 15 residual amount (about 3 micro-micro-farads) just sufficient to make up for losses in the input circuit of the tube, and not more. Capacitive feed back has the effect of decreasing the apparent resistance of the input circuit and thence increasing the current and voltage therein. This should be increased up to a certain point and not beyond, since the more the current is increased, 20 the louder the signal and the more selective 25 the circuits, until a limit is reached, the limit being the stage at which incipient and sustained oscillations take place. The ideal system, therefore, is one in which the energy retransfer ($K' \times V$) is maintained constant 30 over the whole wave length range of the system; and the capacitively tuned system does not meet the requirements because of its variable capacitive coupling coefficient K' .
- 35 In prior systems in which the capacitive grid-plate feed back is controlled, not only is the value of K' variable, but the plate voltage V is variant and in the same direction as K' , producing a squared increase of 40 energy feed back with decreasing wave length, instead of holding the energy retransfer constant as desired. This is due to the fact that the inductive coupling coefficient between the coupled or linked circuits is held constant, causing the output 45 impedance in the plate circuit to decrease with the wave length and consequently the plate voltage increases with the decreasing wave length. The combination of these two 50 factors, therefore, produces a negative resistance reaction in the grid circuit which diminishes at least as fast as the square of the wave length, leaving the input circuit with an extremely high decrement on the 55 longer waves.
- With the principles of my system, however, I am enabled to design the circuits so as to maintain both the capacitive coupling coefficient K' and the plate voltage V constant over the whole wave length range, 60 producing a system in which the energy retransfer due to the grid-plate capacity of the tube may be held substantially invariant
- over the whole wave length range, and may be controlled for tubes of different grid-plate characteristics.
- The features of my system which permit of this capacitive feed back control are the inductive tuning and the inductive coupling coefficient variations produced. By means of my inductively tuned circuits, I am enabled in a manner to be described presently to maintain the capacity of the tunable circuit constant during tuning thereof, permitting the capacitive coupling coefficient K' to 75 be held constant, and by means of the above described variation in the inductive coupling coefficient K , the output impedance (the reflected resistance R'_1) is constant over the whole wave length range, and this latter produces a plate voltage which remains constant, the plate voltage being the product of the output impedance and the oscillating plate current. The plate voltage herein referred to is not the direct current plate voltage but 80 the alternating voltage on the plate which is the product of the output impedance and the oscillating plate current.
- To obtain the optimum conditions for holding the capacitive coupling coefficient K' constant over the whole wave length range, correlated to the inductive tuning of the input circuits I provide means for producing a shunt capacity in each of the input circuits which remains substantially constant during the 90 tuning of the same, this being provided for the antenna input circuit i and for the first and second stage input circuits i' and i'' .
- To achieve the desired results the total shunt capacity of each of the input circuits 100 is made from ten to twenty times and preferably fifteen times the grid-plate capacity of the tube. I have determined that this may be accomplished by placing a condenser in shunt with the secondary L_2 of the vario-transformers V' and V'' of a value of about 80 micro-micro-farads to bring the total shunt capacity of the input circuits i' and i'' to about 150 micro-micro-farads, and referring to Fig. 1 of the drawings, these shunt 110 condensers are indicated respectively as m' and m'' respectively.
- The provision of these shunt condensers each having the above stated comparative magnitude possesses in general the following 115 advantages:
- (a) It makes the wave length calibration of the circuit independent of the tube capacity,
- (b) It creates a capacitive feed back coupling of the right order of magnitude which is a coupling that will neutralize the input

circuit resistance due to the feedback reaction, (c) It offers a ready means of adjusting the total circuit capacity to a predetermined value. This is commercially important in order to have all of the stages of the tube amplifier calibrate the same way.

Although I have selected a value of 150 micro-micro-farads for the total shunt capacity, it will be understood that this may be varied within limits. Experimentally I have found that the best results are to be secured by using a fixed capacity across the grid circuit of approximately 100 micro-micro-farads. The useful range for present day amplifying tubes and for the engineering materials available for the construction of the tuned transformers is from 50 to 150 micro-micro-farads. This applies more particularly to the present broadcasting range of 200 to 575 meters; and for higher wave lengths the shunt grid capacity should be increased approximately proportionately with the wave length. In the present form of my invention I employ, however, a total shunt capacity of 150 micro-micro-farads as stated. A higher efficiency may be secured by the use of a total shunt capacity of 100 micro-micro-farads, but this optimum value is not desirable because of cost considerations.

The selection of this value of shunt capacity is determined on the one hand by the fact that smaller shunt capacities are open to variation in calibration due to a change of vacuum tube, are subject to change of tuning due to change of filament current, and are subject to excessive capacitive feed back which is not easily controllable. The selection is determined on the other hand by the fact that larger shunt capacities make it extremely difficult to obtain the high amplification efficiency with the engineering materials commercially available. This is primarily due to the fact that the high output impedances (10,000 to 20,000 ohms) desired to match the output plate-filament impedance are difficult to build up with high capacity circuits.

The antenna input circuit i is similarly provided with a shunt capacity generally designated as m which is placed in shunt with the variometer V , the shunt capacity having a value of about 60 micro-micro-farads, this capacity functioning to render the tuning of the antenna circuit independent of any capacity changes.

In the preferred embodiment of the invention, the antenna or first input circuit i besides being constructed to maintain a constant capacity during tuning, is designed so as to be rendered independent of the size of the antenna, the construction including means for effecting a virtual decoupling of the first input circuit from the antenna n . This is accomplished by providing a condenser called a series condenser m' in series with

the antenna n and the variometer V , the size of this condenser being about $1/5$ the capacity of a small antenna, or $1/10$ the capacity of a large antenna. With this construction and with the total shunt capacity of the first input circuit i , the capacity of the input circuit has a magnitude which is from four to five times the capacity of the antenna and the series condenser combined. With this recited construction I have found that the variometer V tunes independent of the size of the antenna and with substantially constant coupling to the antenna over the whole wave length range, the capacity of the first input circuit being therefore localized to the variometer. Besides the many advantages of this tuning system hereinbefore described, the rendering of the capacity of all of the input circuits independent of the tuning permits the same dial settings for each of the variometer or variotransformer units, so that a mono-control system is afforded.

With the capacities of the input circuits all maintained invariant over the whole wave length range, it will therefore be seen that the antenna capacitive coupling coefficient is held constant and the capacitive coupling coefficients between the grid and plate circuits of both tuned radio frequency stages are also held constant, producing in combination with the constant plate voltage characteristic, a system in which the product $K' x V$ is substantially constant for each stage; and with this product constant, and assuming other factors such as the resistance of the circuits constant, the energy retransfer or feed back due to the grid plate capacity may be held invariant. In the preferred embodiment of the invention, the energy retransfer in the second tuning stage of the system is held constant, while the energy retransfer in the first tuning stage is made to deviate somewhat from a constant value and more specifically to decrease with increase of wave length so as to compensate for the decrease of losses in the first input circuit which takes place with increase of wave length, it being desired that the energy retransfer be a constant percentage of the losses in such input circuit. It is to compensate for such change or variation of losses that the mutual for the first tuning stage is made to vary at a rate less than the $\frac{3}{2}$ power of the wave length

as heretofore set forth. The change in energy retransfer in this first tuning stage, however, while it is made to vary for compensating purposes, changes in the order of the $\frac{1}{2}$ power of the wave length and may be regarded as substantially constant.

This result of constant capacitive energy feed back produced with my system permits the employment of cascaded tube circuits without means for neutralizing the grid-plate

In cascaded circuits in which the secondary circuit is capacitively tuned, the capacitive coupling co-efficient between the grid and plate circuits of a tube

$$(K' = \sqrt{\frac{C_{sp}^2}{C_s C_p}}, \text{ where } C_{sp} \text{ is small compared with } C_s + C_p)$$

5 instead of remaining constant, will vary with the tuning of the secondary, increasing sharply with the decreasing wave length, with the result that the energy retransfer or feed back increases, this energy retransfer 10 being proportional to $K' \times V$ where V is the voltage on the plate. The ideal condition is where both K' and V are constant, since it is desired that the feed back due to the capacitive coupling be a constant 15 residual amount (about 3 micro-micro-farads) just sufficient to make up for losses in the input circuit of the tube, and not more. Capacitive feed back has the effect of decreasing the apparent resistance of the input circuit and thence increasing the current 20 and voltage therein. This should be increased up to a certain point and not beyond, since the more the current is increased, the louder the signal and the more selective 25 the circuits, until a limit is reached, the limit being the stage at which incipient and sustained oscillations take place. The ideal system, therefore, is one in which the energy retransfer ($K' \times V$) is maintained constant 30 over the whole wave length range of the system; and the capacitively tuned system does not meet the requirements because of its variable capacitive coupling coefficient K' .

35 In prior systems in which the capacitive grid-plate feed back is controlled, not only is the value of K' variable, but the plate voltage V is variant and in the same direction as K' , producing a squared increase of 40 energy feed back with decreasing wave length, instead of holding the energy retransfer constant as desired. This is due to the fact that the inductive coupling coefficient between the coupled or linked circuits is held constant, causing the output 45 impedance in the plate circuit to decrease with the wave length and consequently the plate voltage increases with the decreasing wave length. The combination of these two 50 factors, therefore, produces a negative resistance reaction in the grid circuit which diminishes at least as fast as the square of the wave length, leaving the input circuit with an extremely high decrement on the 55 longer waves.

With the principles of my system, however, I am enabled to design the circuits so as to maintain both the capacitive coupling coefficient K' and the plate voltage V constant over the whole wave length range, 60 producing a system in which the energy retransfer due to the grid-plate capacity of the tube may be held substantially invariant

over the whole wave length range, and may be controlled for tubes of different grid-plate characteristics.

The features of my system which permit of this capacitive feed back control are the inductive tuning and the inductive coupling coefficient variations produced. By means of my inductively tuned circuits, I am enabled in a manner to be described presently to maintain the capacity of the tunable circuit constant during tuning thereof, permitting the capacitive coupling coefficient K' to 75 be held constant, and by means of the above described variation in the inductive coupling coefficient K , the output impedance (the reflected resistance R'_1) is constant over the 80 whole wave length range, and this latter produces a plate voltage which remains constant, the plate voltage being the product of the output impedance and the oscillating plate current. The plate voltage herein referred to is not the direct current plate voltage but 85 the alternating voltage on the plate which is the product of the output impedance and the oscillating plate current.

To obtain the optimum conditions for holding the capacitive coupling coefficient K' constant over the whole wave length range, correlated to the inductive tuning of the input circuits I provide means for producing a shunt capacity in each of the input circuits which remains substantially constant during the 90 tuning of the same, this being provided for the antenna input circuit i and for the first and second stage input circuits i' and i'' .

To achieve the desired results the total shunt capacity of each of the input circuits 100 is made from ten to twenty times and preferably fifteen times the grid-plate capacity of the tube. I have determined that this may be accomplished by placing a condenser in shunt with the secondary L_2 of the vari- 105 transformers V' and V'' of a value of about 80 micro-micro-farads to bring the total shunt capacity of the input circuits i' and i'' to about 150 micro-micro-farads, and referring to Fig. 1 of the drawings, these shunt 110 condensers are indicated respectively as m' and m'' respectively.

The provision of these shunt condensers each having the above stated comparative magnitude possesses in general the following 115 advantages:

(a) It makes the wave length calibration of the circuit independent of the tube capacity,

(b) It creates a capacitive feed back coupling of the right order of magnitude which 120 is a coupling that will neutralize the input

circuit resistance due to the feedback reaction, (c) It offers a ready means of adjusting the total circuit capacity to a predetermined value. This is commercially important in order to have all of the stages of the tube amplifier calibrate the same way.

Although I have selected a value of 150 micro-micro-farads for the total shunt capacity, it will be understood that this may 10 be varied within limits. Experimentally I have found that the best results are to be secured by using a fixed capacity across the grid circuit of approximately 100 micro-micro-farads. The useful range for present- 15 day amplifying tubes and for the engineering materials available for the construction of the tuned transformers is from 50 to 150 micro-micro-farads. This applies more particularly to the present broadcasting range of 20 200 to 575 meters; and for higher wave lengths the shunt grid capacity should be increased approximately proportionately with the wave length. In the present form of my invention I employ, however, a total shunt 25 capacity of 150 micro-micro-farads as stated. A higher efficiency may be secured by the use of a total shunt capacity of 100 micro-micro-farads, but this optimum value is not desirable because of cost considerations.

30 The selection of this value of shunt capacity is determined on the one hand by the fact that smaller shunt capacities are open to variation in calibration due to a change of vacuum tube, are subject to change of tuning 35 due to change of filament current, and are subject to excessive capacitive feed back which is not easily controllable. The selection is determined on the other hand by the fact that larger shunt capacities make it extremely difficult to obtain the high amplification efficiency with the engineering materials 40 commercially available. This is primarily due to the fact that the high output impedances (10,000 to 20,000 ohms) desired to 45 match the output plate-filament impedance are difficult to build up with high capacity circuits.

The antenna input circuit i is similarly provided with a shunt capacity generally 50 designated as m which is placed in shunt with the variometer V , the shunt capacity having a value of about 60 micro-micro-farads, this capacity functioning to render the tuning of the antenna circuit independent of any capacity changes.

In the preferred embodiment of the invention, the antenna or first input circuit i besides being constructed to maintain a constant capacity during tuning, is designed so 60 as to be rendered independent of the size of the antenna, the construction including means for effecting a virtual decoupling of the first input circuit from the antenna n . This is accomplished by providing a condenser 65 called a series condenser m^3 in series with

the antenna n and the variometer V , the size of this condenser being about $\frac{1}{5}$ the capacity of a small antenna, or $\frac{1}{15}$ the capacity of a large antenna. With this construction and with the total shunt capacity of the first 70 input circuit i , the capacity of the input circuit has a magnitude which is from four to five times the capacity of the antenna and the series condenser combined. With this recited construction I have found that the variometer V tunes independent of the size of the antenna and with substantially constant coupling to the antenna over the whole wave length range, the capacity of the first input circuit being therefore localized to the variometer. Besides the many advantages of this tuning system hereinbefore described, the rendering of the capacity of all of the input circuits independent of the tuning permits the same dial settings for each of the variometer or variotransformer units, so that a 80 mono-control system is afforded.

With the capacities of the input circuits all maintained invariant over the whole wave length range, it will therefore be seen that 90 the antenna capacitive coupling coefficient is held constant and the capacitive coupling coefficients between the grid and plate circuits of both tuned radio frequency stages are also held constant, producing in combination 95 with the constant plate voltage characteristic, a system in which the product $K'xV$ is substantially constant for each stage; and with this product constant, and assuming other factors such as the resistance of the 100 circuits constant, the energy retransfer or feed back due to the grid plate capacity may be held invariant. In the preferred embodiment of the invention, the energy retransfer in the second tuning stage of the system is 105 held constant, while the energy retransfer in the first tuning stage is made to deviate somewhat from a constant value and more specifically to decrease with increase of wave length so as to compensate for the decrease 110 of losses in the first input circuit which takes place with increase of wave length, it being desired that the energy retransfer be a constant percentage of the losses in such input circuit. It is to compensate for such change 115 or variation of losses that the mutual for the first tuning stage is made to vary at a rate less than the $\frac{3}{2}$ power of the wave length

as heretofore set forth. The change in energy retransfer in this first tuning stage, however, while it is made to vary for compensating purposes, changes in the order of the $\frac{1}{2}$ power of the wave length and may be regarded as substantially constant.

This result of constant capacitive energy feed back produced with my system permits the employment of cascaded tube circuits without means for neutralizing the grid-plate 130

capacity with tubes having a low grid-plate capacity such as 3 micro-micro-farads. I have discovered that for such tubes and with shunt capacities of 100 micro-micro-farads, the feed back is of the right order throughout the wave length range.

With tubes of larger grid-plate capacity and approximately 8 micro-micro-farads, the above described features of my invention may be combined with capacitive feed back control means for compensating for the remaining grid-plate capacity (5 out of 8 micro-micro-farads), and for maintaining the retransferred energy in such tubes constant over the whole wave length range; and this, as heretofore set forth, comprehends a further prime object of my present invention.

The capacitive feed back control means which I combine with the inductive tuning and change of coupling coefficient features of my invention is that described and claimed in my copending application Ser. No. 607,046 heretofore referred to, the resulting system being shown in Fig. 6 of the drawings. In Fig. 6 of the drawings, I show a radio receiving circuit having two stages of radio frequency amplification similar to that heretofore described in connection with Fig. 1, the parts of which are indicated by similar reference characters, the system in Fig. 6 of the drawings further including an audio stage following the rectifying device a^2 . The amplifying circuits in Fig. 6 are substantially the same as that shown in Fig. 1, and are also indicated by similar reference characters, the variometer V being of the type shown in Fig. 3, the variotransformer V' that shown in Fig. 4, and the variotransformer V² that shown in Fig. 5 of the drawings.

For controlling, compensating or neutralizing the excess grid-plate capacitive feed back, I provide means inductively related to the variotransformers V' and V² for producing a charge equal in magnitude but opposite in sign to the charge carried to the grid from the plate and for impressing such charge on the grid of each amplifying tube. This is accomplished by first creating a potential opposite to the potential on the plate and impressing the said potential on a condenser which is connected to the grid of the tube, the product of the potential and the capacity of the condenser being made equal to the excess charge transferred to the grid from the plate due to the inherent capacity therebetween.

Referring now to Fig. 6 of the drawings, I show such neutralizing means as comprising a coil R—P hereinafter called the reverse potential coil, inductively related to the end stator s_1 of the variotransformer V', to which stator coil the primary L₁ is inductively coupled, the construction being such that a potential is created by the R—P coil which is made equal in phase and amplitude and opposite in sign to the potential on the plate 22;

and the reverse potential coil is connected by means of a conductor 55 to a plate d of a condenser 56, another plate e of which is connected by means of the conductors 57 and 58 to the grid 21 of the tube a , the other end of the reverse potential coil being connected to the B battery by means of the conductor 28. The plate e of the condenser 56 preferably comprises a rotor so that the capacity of this condenser may be varied to make the same equal to that capacity between the grid and plate of the tube which is desired to be compensated for. The reverse potential coil may if desired be coupled to the primary L₁, but in the preferred construction both the reverse potential and primary coils are similarly and equally coupled to the end stator coil s_1 of the variotransformer, as clearly shown in Figs. 4 and 6 of the drawings.

For neutralizing the excess grid-plate capacity feed back of the tube a' , the variotransformer V² is similarly provided with a reverse potential coil R—P, which however is coupled to the end stator coil s_1 by being arranged at the end of the variotransformer unit as clearly shown in Figs. 5 and 6 of the drawings, this reverse potential coil being connected at one end to the B battery by means of the conductor 38 and at the other end to the plate d of the condenser 56' by means of the conductor 59, the plate e of which condenser is connected to the grid 21 of the tube a' by means of the conductors 60 and 23. Here too it will be noted that both the primary coil L₁ and the reverse potential coil R—P are coupled equally to the end stator coil s_1 .

By the provision of this means, it will be seen that the grid of each tube is supplied with an electric charge which is equal and opposite to the charge thereon resulting from the grid-plate capacity, and it will be further noted that the neutralizing charge varies in correspondence with the varying charge on the plate in the operation of the circuits so that the energy feed back is compensated for in all the frequency variations of the grid and plate circuits.

As above stated, the neutralizing condensers 56 and 56' are made adjustable for the purpose of varying the charge impressed on the grid. For the purpose of preventing the variation of capacity of these condensers from varying the tuning characteristics of the grid or input circuit, my invention further includes means for varying the capacity of the input circuit simultaneously and in correspondence with the varying of the capacity in the charge equalizing circuit. This result is accomplished in the preferred practice of my invention by making the condensers 56 and 56' in the form of three-element condensers each having an additional plate f which is connected to the filament end of the grid circuit by means of the conductors 61, 130

62 for the condenser 56 and conductors 63, 64, 24, 25 and 62 for the condenser 56'. The construction of the plates *e*, *f* and *d* of each condenser is such that when the plate *e* is moved in one direction, the capacity between the plates *e* and *d* is increased and the capacity between the plates *e* and *f* is correspondingly decreased, and as the plate *e* is moved in the opposite direction, the capacity between the plates *e* and *f* is increased while the capacity between the plates *e* and *d* is correspondingly decreased. In view of the negligible impedance of the reverse potential coil as compared with the impedance of the grid coil, the change in capacity between the plates *e* and *f* is normally effective for modifying the capacity of the grid circuit, and by this construction the grid circuit capacity may be maintained constant during adjustment of the plate *e* and hence during the variation of the charge impressed upon the grid. The three-plate condenser of my invention preferably has a construction described and claimed in my copending application Ser. No. 680,465 filed Dec. 13, 1923.

In addition to the two radio frequency stages, I show in Fig. 6 an audio frequency stage comprising an amplifying tube *a*³ having an input circuit *i*³ coupled to the output circuit *o*² of the tube *a*² by means of a transformer *t*, the audio frequency tube having an output circuit *o*³ provided with the usual telephone switch 65. In order to permit a shift of the telephones from the audio to the detecting stage of the system, the output circuit *o*² is provided with the usual three-point switching device 66.

From the above it will further be seen that with my inductively tuned system, a stability of "feed back" is obtained. The above considerations show that the total secondary resistance *R* should increase with the wave length and that the percentage which remains after the tube feed back reaction should be approximately equally divided between real and primary reflected resistances *R*₂ and *R*'₂ respectively. With the engineering materials commercially available it is not always possible to obtain low enough values of *R*₂ and *R*'₂. Advantage should be taken, therefore, of the reduction of resistance *R*_{2P} due to the tube grid-plate feed back reaction. The great advantage of the inductively tuned system is that, as already remarked, with low capacity tubes the percentage reduction is approximately correct over the whole wave length range. With high capacity tubes using my feed back compensator system, a fraction of the feed back reaction may be left active and the same fraction is effective for the whole wave length range.

Two conditions should be satisfied in order to secure stable operation, by which is meant avoiding oscillation or incipient oscillation conditions of the amplifier. The first is that

*R*₂ plus *R*'₂ be always greater than *R*_{2P}. The second is that *R*₂ as above stated be comparable in magnitude with *R*'₂. The first condition means that the secondary circuit always has a net positive resistance; for, when the net resistance is zero or negative any oscillation set up in the secondary circuit persists indefinitely or increases its amplitude until the voltages exceed the linear limits of the tube characteristics. The second condition is one which permits the first to be practically realized. If a circuit be constructed having low *R*₂ and with a relatively high *R*'₂ and the sum of these be almost completely negated by *R*_{2P}, then the balance will depend primarily upon the constancy of *R*'₂. This reflected resistance, however, is again dependent upon the filament plate resistance, which varies somewhat with the amplitude of the signal, with the *B* battery voltage, and quite sharply with the filament current. The usual and best way of controlling volume is by adjustment of the radio frequency amplification through the adjustment of the filament current. Decreasing the filament current decreases the electron emission, increases the plate filament resistance and therefore decreases *R*'₂. A slight variation of the filament current of the preceding tube will carry the net resistance of the secondary circuit down to zero or to a negative value with resulting oscillations.

As heretofore stated, it is a further principal object of my invention to provide a radio receiving set having a number of inductively tuned stages arranged in cascade, in which intermagnetic coupling between the stages is effectively obviated, permitting independence of adjustment for each stage and permitting the units of all the stages to be mounted closely together without producing magnetic coupling troubles. I have discovered that when the double D variometers of adjacent stages are turned at right angles one with respect to the other with their axes parallel or with their axes coaxial, substantially all residual magnetic coupling between the stages is effectively eliminated. It will be understood that the variometers of the double D type have little intermagnetic coupling to begin with, especially so when the variometers are set with their axes parallel, the residual coupling diminishing very rapidly with increasing distance between the variometer axes. When the double D coils of adjacent variometer or variotransformer units, however, are turned at right angles, this residual is practically nullified. The reason for this will be readily appreciated when it is seen that if the coils of all the units were arranged in the same way, the effect of one of the D coil sections of one unit upon a D section of an adjacent unit would be different than the effect of the other D section of the first unit upon the said D section of the adj-

cent unit. Therefore by rotating one of the units 90° relatively to the other, the D section of one unit has the same coupling effect on the two D's of the adjacent unit, resulting in 5 magnetic neutralizing effects, the neutralization being the result of the fact that the magnetic fields in the two D sections of a given unit are in opposite directions. With this arrangement, therefore, all residual magnetic 10 coupling between the units is practically eliminated or at least minimized to the lowest degree; and the units may be closely mounted without having magnetic coupling troubles.

Where a variometer and a plurality of 15 variotransformers are arranged in series, as in Figs. 1 and 6, I have found that the optimum condition of elimination of residual coupling is reached when the D coils (that is to say the stator D coils and the rotor D coils 20 for the same setting) of the intermediate unit are arranged at right angles to the D coils of the outside units. This phase of my invention is clearly depicted in Fig. 1 of the drawings, in which it will be seen that the coils of 25 the variotransformer V' are arranged at an angle of 90° to the coils of the variometer V and the variotransformer V^2 .

Although the position of the rotor coils 30 varies when the stage is tuned, it will be understood that the rotor coils of the different stages bear to one another the desired relation, since the circuits are designed, as hereinbefore fully set forth, to tune in the same way and with substantially the same 35 rotor settings.

The manner of making and using the 40 tuned radio frequency system of my invention will in the main be fully apparent from the above detailed description thereof taken in conjunction with the operations as heretofore outlined. It will be further apparent that while I have disclosed in detail the construction and arrangement of the system and the parts thereof with the particular magnitudes or sizes of the capacities and inductances involved, that my invention is not to 45 be limited thereto, and that changes may be made within wide limits as hereinbefore set forth without varying from the principles of 50 my invention as defined in the following claims.

I claim:

1. The combination of an electron discharge device having a cathode, an anode 55 and a grid, a circuit connected to the anode of the device and a second circuit coupled to the said anode circuit, the said coupled circuits including mechanism predetermined in its operation for simultaneously varying in 60 the same direction the coupling coefficient of said circuits and the wave length of the said second circuit.

2. The combination of an electron discharge device having a cathode, an anode and

a grid, a circuit connected to the anode of the 65 device, a second circuit, means coupling said second circuit to the said anode circuit, means for tuning said coupled circuits and mechanism connecting both of said means for simultaneously varying in the same direction 70 the coupling coefficient between said circuits and the wave length of the said second circuit.

3. The combination of an electron discharge device having a cathode, an anode and 75 a grid, a circuit connected to the anode of the device and a second circuit inductively coupled to the said anode circuit, the said coupled circuits including mechanism for inductively tuning the said second circuit and 80 for simultaneously varying the said inductive coupling in a predetermined manner.

4. The combination of an electron discharge device having a cathode, an anode and a grid, a circuit connected to the anode of the 85 device and a second circuit coupled to the said anode circuit, the said coupled circuits including mechanism predetermined in its operation for simultaneously and progressively varying in the same direction the said 90 coupling and the wave length of the said second circuit, whereby the coupling is relatively loose on the shorter wave lengths and relatively tight on the longer wave lengths.

5. The combination of an electron discharge device having a cathode, an anode and a grid, a circuit connected to the anode of the device and a second circuit coupled to the said anode circuit, the said coupled circuits including a variotransformer having 100 a primary in the anode circuit and a variable secondary in the second circuit and means for simultaneously varying the coupling coefficient between the primary and secondary circuits and the tuning of the second circuit. 105

6. In combination, a plurality of electron discharge tube circuits, means for inductively linking the circuits in cascade, means for tuning the coupled circuits and mechanism connecting both of said means for simultaneously varying in the same direction the coupling coefficient between adjacent circuits and the wave length of one of the circuits, whereby the coupling is relatively loose on 110 short wave lengths and relatively tight on long wave lengths.

7. In combination, an electron discharge device having an output circuit and an input circuit, and means for linking the circuits in cascade including mechanism for simultaneously and progressively varying in a predetermined manner the coupling coefficient between adjacent circuits and the wave length of one of the circuits in the same direction. 115

8. The combination of a plurality of electron discharge devices each having a cathode, an anode and a grid, and means for linking the devices in cascade including a circuit 120

- connected to the anode of one device and a circuit inductively coupled to the anode circuit and connected to the grid of the second device, the said coupled circuits including mechanism for inductively tuning the said grid circuit and for simultaneously varying the said inductive coupling in a predetermined manner.
9. The combination of a plurality of electron discharge devices each having a cathode, an anode and a grid, and means for linking the devices in cascade including a circuit connected to the anode of one device and a circuit coupled to the anode circuit and connected to the grid of the second device, the said coupled circuits including mechanism predetermined in its operation for simultaneously varying in the same direction the coupling coefficient between said circuits and the wave length of the said grid circuit.
10. The combination of a plurality of electron discharge device each having a cathode, an anode and a grid, and means for linking the devices in cascade including a circuit connected to the anode of one device and a circuit coupled to the anode circuit and connected to the grid of the second device, the said coupled circuits including a variotransformer having a primary in said anode circuit and a variable secondary in said grid circuit and means for simultaneously varying the coupling coefficient between the primary and secondary circuits and the tuning of the secondary.
11. In combination, a plurality of circuits and means for linking the circuits in cascade including mechanism predetermined in its operation for varying the wave length of one of the circuits and for simultaneously varying the coupling coefficient between the circuits substantially proportionately to and in the same direction as the wave length variation.
12. The combination of an electron discharge device having a cathode, an anode and a grid, a circuit connected to the anode of the device and a second circuit coupled to said anode circuit, the said coupled circuits including means for varying the wave length of said second circuit, means for varying the coupling of the circuits and mechanism connecting both of said means for simultaneously varying the coupling coefficient between the circuits substantially proportionately to and in the same direction as the wave length variation.
13. The combination of an electron discharge device having a cathode, an anode and a grid, a circuit connected to the anode of the device and a second circuit inductively coupled to said anode circuit, the said coupled circuits including mechanism for inductively varying the wave length of said second circuit and for simultaneously varying the coupling coefficient between the circuits substantially proportionately to and in the same direction as the wave length variation.
14. In combination, a series of cascaded circuits including a plurality of variotransformers each linking adjacent circuits of the series, one of the variotransformers including mechanism for simultaneously varying the coupling coefficient of the circuits linked thereby in the same direction with the variation of the wave length in one of said linked circuits and the other variotransformer including mechanism for simultaneously varying the coupling coefficient of the circuits linked thereby in the same direction with and proportionately to the variation of the wave length in one of the circuits linked thereby.
15. In combination, a series of cascaded circuits including a plurality of structures each linking adjacent circuits of the series, one of the said structures including mechanism for simultaneously varying the coupling coefficient of the circuits linked thereby in the same direction with and less than proportionately to the variation of the wave length in one of said linked circuits and the other of said structures including mechanism for simultaneously varying the coupling coefficient of the circuits linked thereby in the same direction with and proportionately to the variation of the wave length in one of the circuits linked thereby.
16. The combination of an electron discharge device having a cathode, an anode and a grid, a circuit connected to the anode of the device and a second circuit coupled to said anode circuit, the said coupled circuits including mechanism for varying the wave length of said second circuit and for simultaneously varying the coupling coefficient between the circuits less than proportionately to and in the same direction as the wave length variation.
17. The combination of an electron discharge device having a cathode, an anode and a grid, an output circuit connected to the anode of the device and an input circuit coupled to the said output circuit, the said coupled circuits including mechanism for simultaneously varying in a predetermined manner the coupling coefficient between the circuits and the tuning of the input circuit, the said output circuit having an impedance which is substantially one-half the plate-filament impedance.
18. The combination of a plurality of electron discharge devices each having a cathode, an anode and a grid, and means for linking the devices in cascade including an output circuit connected to the anode of one device and an input circuit coupled to the output circuit and connected to the grid of the second device, the said coupled circuits including mechanism for simultaneously varying in a predetermined manner the coupling coefficient between the circuits and the tuning of

- 5 said input circuit, the impedance of the said output circuit being substantially one-half the plate filament impedance.
19. The combination of an electron discharge device having a cathode, an anode and a grid, an output and primary circuit connected to the anode of the device and an input and secondary circuit coupled to the said primary circuit, the said coupled circuits including mechanism for simultaneously varying in a predetermined manner the coupling coefficient between the circuits and the tuning of the secondary circuit, the said circuits having resistances of a magnitude 10 such that the resistance reflected from the primary into the secondary is of the same order of magnitude as the ohmic resistance of the secondary.
20. The combination of an electron discharge device having a cathode, an anode and a grid, an input circuit connected to the grid, an output circuit connected to the anode, capacity means in the said input circuit having a total shunt capacity value which is of a magnitude of from ten to twenty times the grid-plate capacity of the device, and means 25 for tuning the said input circuit while keeping the said total shunt capacity value substantially constant.
21. The combination of an electron discharge device having a cathode, an anode and a grid, an input circuit connected to the grid, an output circuit connected to the anode, a variable inductance in the said input circuit 30 for tuning the same, and capacity means in said input circuit having a total shunt capacity value which remains substantially constant during tuning of the circuit and of a magnitude of from ten to twenty times the grid-plate capacity of the device.
22. The combination of an electron discharge device having a cathode, an anode and a grid, an input circuit connected to the grid including a variable inductance for tuning the input circuit, an output circuit connected to the anode, a condenser in shunt with the variable inductance substantially equal in magnitude to the capacity of the remaining part of the input circuit.
23. The combination of an electron discharge device having a cathode, an anode and a grid, an input circuit connected to the grid including a variable inductance for tuning the input circuit, an output circuit connected 45 to the anode, a condenser in shunt with the variable inductance having a capacity from ten to twenty times the grid-plate capacity of the device.
24. In combination, a plurality of electron discharge devices each having a cathode, an anode and a grid, and means for linking the said devices comprising coupled anode and grid circuits including a variotransformer having a primary in the anode circuit and a 50 variable secondary in the grid circuit for tuning the latter, and a condenser in shunt to the variable secondary of a magnitude substantially equal to the capacity of the remaining part of the grid circuit.
25. The combination of an electron discharge device having a cathode, an anode and a grid, an input circuit connected to the grid, an output circuit connected to the anode, a circuit coupled to the said output circuit and including mechanism for inductively tuning 55 the coupled circuit, and feed-back control means for compensating for the capacity coupling between the grid and plate of said device.
26. The combination of an electron discharge device having a cathode, an anode and a grid, an input circuit connected to the grid, an output circuit connected to the anode, a circuit inductively coupled to the said output circuit and including mechanism for inductively tuning the coupled circuit, and feed-back control means inductively associated with both the output circuit and the coupled circuit for compensating for the capacity coupling between the grid and plate of said 60 device.
27. The combination of an electron discharge device having a cathode, an anode and a grid, an input circuit connected to the grid, an output circuit connected to the anode, a circuit coupled to the said output circuit and including mechanism for inductively tuning the coupled circuit, and feed-back control means for compensating for the capacity coupling between the grid and plate of said 65 device, the said compensating means comprising a condenser connected to the grid and a coil inductively coupled to said coupled circuit and connected to said condenser.
28. The combination of an electron discharge device having a cathode, an anode and a grid, an input circuit connected to the grid, an output circuit connected to the anode, a circuit coupled to the said output circuit and including mechanism for inductively tuning the coupled circuit and for simultaneously varying the coupling coefficient, and feed-back control means for compensating for the capacity coupling between 70 the grid and plate of said device.
29. The combination of an electron discharge device having a cathode, an anode and a grid, a circuit, and means for linking the circuit to the anode of the electron discharge device, the said means comprising a variotransformer having a primary connected to the anode of said device and a variable secondary in said circuit, and feed-back control means inductively related to said variotransformer for compensating for the grid-plate 75 capacity of said device.
30. The combination of an electron discharge device having a cathode, an anode and a grid, a circuit, and means for linking the circuit to the anode of the electron discharge 80 device.

- device, the said means comprising a variotransformer having a primary connected to the anode of said device and a variable secondary in said circuit, and means for compensating for the grid-plate capacity of said device comprising a coil inductively related to said variotransformer and a condenser connecting the coil to the grid.
31. The combination of an electron discharge device having a cathode, an anode and a grid, a circuit, and means for linking the circuit to the anode of the electron discharge device, the said means comprising a variotransformer having a primary connected to the anode of said device and a variable secondary in said circuit, and means having a coil inductively related to the secondary of said variotransformer for compensating for the grid-plate capacity of said device, the said coil and the said primary being inductively coupled in like manner to the said secondary.
32. The combination of an electron discharge device having a cathode, an anode and a grid, a circuit, and means for linking the circuit to the anode of the electron discharge device, the said means comprising a variotransformer having a primary connected to the anode of said device and a variable secondary in said circuit made up of stator and rotor double D coils, and means inductively related to a stator coil of said variable secondary for compensating for the grid-plate capacity of said device.
33. The combination of an electron discharge device having a cathode, an anode and a grid, a circuit, and means for linking the circuit to the anode of the electron discharge device, the said means comprising a variotransformer having a primary connected to the anode of said device and a variable secondary in said circuit made up of stator and rotor double D coils, and means inductively related to a coil of said variable secondary for compensating for the grid-plate capacity of said device.
34. The combination of an electron discharge device having a cathode, an anode and a grid, a circuit, and means for linking the circuit to the anode of the electron discharge device, the said means comprising a variotransformer having a primary connected to the anode of said device and a variable secondary in said circuit made up of stator and rotor double D coils, and means including a coil inductively related to a stator coil of said variable secondary for compensating for the grid-plate capacity of said device, the said primary being also inductively related to said stator coil.
35. The combination of an electron discharge device having a cathode, an anode and a grid, an antenna circuit connected to the grid, an output circuit connected to the anode, the said antenna circuit having a variable inductance for tuning purposes and

having a total shunt capacity which remains substantially constant during tuning of the circuit and of a magnitude of from ten to twenty times the grid-plate capacity of the device.

36. The combination of an electron discharge device having a cathode, an anode and a grid, an antenna circuit connected to the grid, an output circuit connected to the anode, the said antenna circuit having a variable inductance for tuning purposes and having a total shunt capacity which remains substantially constant during tuning of the circuit and of a magnitude of from fifty to one hundred and fifty micro-micro-farads.

37. The combination of an electron discharge device having a cathode, an anode and a grid, an output circuit connected to the anode, said output circuit having a predetermined impedance, and a second circuit coupled to the anode circuit, the said coupled circuits including mechanism for tuning the second circuit while maintaining the output impedance of the output circuit substantially constant.

38. The combination of an electron discharge device having a cathode, an anode and a grid, an output circuit connected to the anode, said output circuit having a predetermined impedance, and a second circuit inductively coupled to the anode circuit, the said coupled circuits including mechanism for inductively tuning the second circuit while maintaining the output impedance of the output circuit substantially constant.

39. The combination of an electron discharge device having a cathode, an anode and a grid, an output circuit connected to the anode and a second circuit inductively coupled to the anode circuit the said coupled circuits including mechanism for tuning the second circuit having ohmic resistance and mutual inductance quantities which maintains the output impedance of the output circuit substantially constant.

40. The combination of an electron discharge device having a cathode a plate and a grid, an input circuit connected to the grid, an output circuit connected to the plate, another circuit coupled to the plate circuit, means for compensating for the capacitive feed back reaction due to the grid-plate capacity, the said coupled circuits including mechanism for tuning the said other circuit without changing the capacity thereof whereby the capacitive coupling coefficient between the input and output circuits remains constant during such tuning of the said other circuit.

41. The combination of an electron discharge device having a cathode, a plate and a grid, an input circuit connected to the grid, an output circuit containing impedance connected to the plate, another circuit coupled to the plate circuit and means for tuning the

said other circuit and for compensating for the grid-plate capacity, the said means including mechanism for maintaining the product of the output impedance, the oscillating 5 plate current and the capacitive coupling coefficient between the grid and plate circuits substantially constant during the tuning of said other circuit.

42. The combination of an electron discharge tube having a cathode, a plate and a grid, a grid circuit connected to the grid of the tube, an untuned plate circuit connected to the plate of the tube, a third circuit embodying means for variably tuning the same, 10 means coupling the said untuned plate circuit to said tunable circuit, and means for varying the coupling of said coupling means for compensating the effects resulting from the varying of said tuning means.

20 43. The combination of an electron discharge tube having a cathode, a plate and a grid, a grid circuit connected to the grid of the tube, an untuned plate circuit connected to the plate of the tube, a third circuit embodying means for variably tuning the same, 25 means coupling the said plate circuit to said tunable circuit, and means for varying the said coupling means as the said tuning means is varied.

30 44. The combination of an electron discharge tube having a cathode, a plate and a grid, a grid circuit connected to the grid of the tube, a plate circuit connected to the plate of the tube, a third and tunable circuit embodying means for variably tuning the same, 35 means coupling the said plate circuit to said tunable circuit, and means for varying the coupling of said coupling means, the said plate circuit comprising a primary having a natural frequency which is greater than the 40 highest frequency of the frequency range through which said tunable circuit is tunable, the said primary being coupled to said tunable circuit so that a change of coupling be- 45 tween the primary and the tunable circuit is unaccompanied by a change of capacity across said tunable circuit.

45. The combination of an electron discharge tube having a cathode, a plate and a 50 grid, a grid circuit connected to the grid of the tube, a plate circuit connected to the plate of the tube, a third and tunable circuit embodying means for variably tuning the same, means coupling the said plate circuit to said 55 tunable circuit, and means for varying the coupling of said coupling means, the said plate circuit comprising an untuned plate coil primary having a natural frequency beyond the frequency range through which said tun- 60 able circuit is tunable, the said primary being coupled to the low potential end of said tunable circuit whereby a change of coupling be- 65 tween the primary and the tunable circuit is unaccompanied by a change of capacity across said tunable circuit.

46. A radio circuit system comprising a plurality of stages arranged in cascade or series, a transformer embodying a primary and a secondary coupling one of said stages to an adjacent stage, means for tuning the 70 circuit of said adjacent or secondary stage over a range of frequencies, means for varying the coupling between the primary and the secondary of the transformer, the constants of the coupled stages including a natural frequency for the transformer primary which is greater than the highest frequency of the frequency range through which the secondary stage is tunable, the said primary being coupled to said secondary so that a change 75 of coupling between the primary and secondary of the transformer is unaccompanied by a change of capacity across the tuned secondary stage.

47. A radio circuit system comprising a 85 plurality of stages arranged in cascade or series, a transformer embodying a primary and a secondary having a high step-up ratio coupling one of said stages to an adjacent stage, the low potential end of the secondary 90 stage being connected to ground, means for tuning the circuit of said adjacent or secondary stage over a range of frequencies, means for varying the coupling between the primary and the secondary of the transformer, the constants of the coupled stages including a natural frequency for the transformer primary which is beyond or outside 95 of the frequency range through which the secondary stage is tunable, the said primary 100 being coupled to the ground potential end of said secondary.

48. A radio circuit system comprising a plurality of stages arranged in cascade or series including an electron discharge tube 105 stage, a transformer embodying a primary and a secondary having a high step-up ratio coupling the tube stage to an adjacent stage, means for tuning the circuit of said adjacent or secondary stage over a range of frequencies, means for varying the coupling between the primary and the secondary of the transformer, the constants of said coupled stages including a natural frequency for the transformer primary which is beyond or outside 110 of the frequency range through which the secondary stage is tunable, the said primary being coupled to the low potential end of said secondary.

49. A radio circuit system comprising a 120 plurality of stages arranged in cascade or series including an electron discharge tube stage, a transformer embodying a primary and a secondary coupling the tube stage to an adjacent stage, means for tuning the circuit of said adjacent or secondary stage over a range of frequencies, means connecting the low potential end of the secondary stage to ground, means for varying the coupling between the primary and the secondary of the 125 130

transformer, the constants of said coupled stages including a natural frequency for the transformer primary which is greater than the highest frequency of the frequency range 5 through which the secondary stage is tunable, the said primary being coupled to the ground potential end of said secondary.

50. A radio circuit system comprising a plurality of stages arranged in cascade or 10 series including a vacuum tube stage, a transformer embodying a primary and a secondary coupling the tube stage to an adjacent stage, means for tuning the circuit of said adjacent or secondary stage over a range of frequencies, means for varying the coupling between 15 the primary and the secondary of the transformer, the constants of the coupled stages including an input conductance for the transformer at resonance substantially higher than 20 the plate conductance of the vacuum tube, the said primary being coupled to said secondary so that a change of coupling between 25 the primary and secondary of the transformer is unaccompanied by a change of capacity across the tuned secondary stage.

51. A radio circuit system comprising a plurality of stages arranged in cascade or 30 series including a vacuum tube stage, a high step-up ratio transformer embodying a primary and a secondary coupling the tube stage to an adjacent stage, means for tuning the circuit of said adjacent or secondary stage over a range of frequencies, means for varying 35 the coupling between the primary and the secondary of the transformer, the constants of the coupled stages including an input conductance for the transformer at resonance substantially higher than the plate conductance of the vacuum tube, means con-

necting the low potential end of the secondary 40 stage to ground, the said primary being coupled to the ground potential end of said secondary.

52. The method of operating a tuned radio frequency amplifier including a vacuum tube 45 and an output transformer associated therewith which consists in arranging the input conductance of said output transformer at resonance so that it is substantially higher in value than the plate conductance of the 50 vacuum tube, in tuning the secondary of said transformer and in varying the coupling between the primary and secondary of said transformer without appreciably changing the effective capacity across the tuned sec- 55 ondary of the transformer.

53. The method of operating a tuned radio frequency amplifier including a vacuum tube whose plate circuit is connected to the input terminals of an electric coupling system, and 60 a second vacuum tube whose grid is connected to the output terminals of said coupling system which consists in arranging said coupling system to step-up the voltage at resonance and to have an input conductance at reso- 65 nance substantially higher in value than the plate conductance of the first mentioned vacuum tube, in tuning the secondary of said coupling system and in varying the coupling between the primary and secondary of said 70 coupling system without appreciably changing the effective capacity across the tuned sec- 75 ondary of the coupling system.

Signed at New York city, in the county of New York and State of New York, this 24th day of May, A. D. 1924.

LESTER L. JONES.
